DESIGN FOR A GARMENT HANGER

John Bolten, Andover, Mass.

Application September 17, 1945, Serial No. 122,131

Term of patent 14 years

(Cl. D80—8)

To all whom it may concern:

Be it known that I, John Bolten, a citizen of the United States, residing at Andover, county of Essex, State of Massachusetts, have invented a new, original, and ornamental Design for Garment Hangers, of which the following is the specification, reference being had to the accompanying drawing, forming part thereof, wherein

Fig. 1 is a side elevational view of a garment hanger showing my new design, and

Fig. 2 is a vertical sectional view on the line 2—2, Fig. 1.

I claim:

The ornamental design for a garment hanger, substantially as shown.

JOHN BOLTEN.
